HAND-HELD HAIR DRYER

Walter C. Anderson, West Redding, Conn., assignor to
General Electric Company

Filed Oct. 11, 1972, Ser. No. 296,616

Term of patent 7 years

Int. Cl. D28—03

U.S. Cl. D86—10 F

FIG. 1.

FIG. 2.

FIG. 3.

FIG. 4.

FIG. 5.

FIG. 6.

FIG. 7.

FIG. 1 is a perspective view of a hand-held hair dryer embodying my new design;

FIG. 2 is a front elevational view thereof;

FIG. 3 is a rear elevational view thereof;

FIG. 4 is a bottom plan view thereof;

FIG. 5 is a top plan view thereof;

FIG. 6 is a right side elevational view thereof; and

FIG. 7 is a left side elevational view thereof.

I claim:

The ornamental design for a hand-held hair dryer, substantially as shown.
